Stinson E. Trott.

UNITED STATES PATENT OFFICE.

STINSON E. TROTT, OF WILMINGTON, ILLINOIS.

PROCESS OF CARBONIZING PAPER.

SPECIFICATION forming part of Letters Patent No. 319,353, dated June 2, 1885.

Application filed February 6, 1884. (Specimens.)

To all whom it may concern:

Be it known that I, STINSON E. TROTT, a citizen of the United States of America, residing at Wilmington, in the county of Will 5 and State of Illinois, have invented certain new and useful Improvements in Carbonized Paper and Mode of Making Same, of which the following is a specification, reference being had therein to the accompanying drawing.

- 10 The figure is a vertical cross-sectional view. This invention consists in a method for carbonizing paper for building and other analogous purposes and rendering it impervious to moisture and less destructible for wear on 15 floors, &c. In the drawing a simple device is shown and intended more to illustrate the method and means of treating the paper to produce the result than as any particular invention, except 20 so far as to the means of heating the carbonizing-rolls.

25 A represent a pair of hollow rolls of a paper-machine, such as are heated by steam admitted through their journals in the ordinary manner.

30 B B are a pair of solid rolls, the lower one of which is intended to be heated by a flame, F, which may be of any kind or applied in any form so it will heat the roll.

35 C is a sheet of straw-board paper, which, as it emerges from between the rolls A A, passes down under a roller in vat D, and from thence out between the rolls B B. The vat D contains a compound or mixture of rubber, asphaltum, and sulphur, the proportions of which can be varied to be the most effective for the kind and quality of paper used. As the paper passes through this compound or mixture, it becomes thoroughly saturated with 40 it, and then immediately passes between the rolls B B, the lower one of which in this case is heated to a high enough temperature to carbonize the saturated paper to a sufficient degree to render it very compact, hard, and im-

pervious to moisture, but not carbonized to 45 such a degree as to destroy the fiber and texture of the paper.

The object of using a flame to heat the roll B, or both of them, if desired, is that it is not possible to raise the temperature of a set of 50 rolls by steam to such a degree as to produce carbonization of the paper and the substance with which it is saturated.

The paper, when thus treated and carbonized, forms a hard dense substance capable of 55 a high degree of polish, well suited for use on floors, roofs, walls, &c., almost indestructible so far as the action of the weather is concerned.

In the device for so treating the paper any 60 number of rolls may be used. Both the upper as well as the lower rolls may be heated by a flame; or the initial set may be heated by steam when less degree of temperature is required at first after the paper leaves the bath.

The compounds named may be substituted 65 by others that may be their equivalent and will produce said result.

I am aware that it is not new to simply saturate paper with the materials named, and hence I do not claim it is new simply to so saturate 70 the paper without carbonizing the composition, as stated.

Having thus described my invention, what I 75 claim as new, and desire to secure by Letters Patent, is as follows, to wit:

In the manufacture of incandescents, the method described of producing a carbonized paper by passing the paper through a compound or mixture of rubber, asphaltum, and sulphur, and then passing the paper so saturated between rolls heated to such degree as to carbonize the same, and forming the incandescent therefrom, substantially as and for the purpose set forth.

STINSON E. TROTT.
